UNITED STATES PATENT OFFICE.

ERVIN L. BOETTLER, OF SAPULPA, OKLAHOMA.

FISHING TOOL.

Application filed February 27, 1926. Serial No. 91,279.

This invention relates to working barrels and more particularly to supplemental working barrels and has for an important object thereof the construction of a supplementary 5 working barrel so that the same may be readily withdrawn from a well.

Supplementary working barrels are barrels employed within the usual working barrel when the usual working barrel becomes 10 so worn that it will not operate properly. These supplementary working barrels are only inserted in the usual working barrel where the conditions are such that removal of the working barrel is an extremely difficult 15 and expensive operation. For example, the casing, to the lower end of which the working barrel is attached, may be so worn or rotted that it would be only possible to pull the same in sections and as a result 20 of extensive fishing operations. It will, therefore, be obvious that where these supplementary working barrels are employed, some means must be provided for removing the supplementary working barrel in event 25 the rod line, by means of which the working barrel of the supplementary barrel is operated, happens to part within the working barrel as sometimes occurs. A further object of the invention is to provide a construction 30 of this character which may be employed with but a slight modification of the ordinary construction of the upper head end of the supplementary barrel.

A further object of the invention is to 35 provide a novel and improved fishing tool for coaction with the modified barrel head.

These and other objects I attain by the construction shown in the accompanying drawings, wherein for the purpose of illustration is shown a preferred embodiment of 40 my invention and wherein:—

Figure 1 is a vertical sectional view 45 through the upper end of a working barrel constructed in accordance with my invention;

Figure 2 is a view showing the manner in which the socket engages the head of the barrel.

Referring now more particularly to the 50 drawings, the numeral 10 generally indicates a working barrel and 11 the head therefor which is threaded into the upper end of the barrel. The head 11 is provided with oil openings 12 which are normally sealed by 55 a cup-like washer 13 which is slidable on a stem 14 threaded through the head 11 axially

thereof. The valve 13 acts as a check, opening as the traveling valve moves upwardly to permit fluid to pass from the barrel and then returning to prevent this fluid from returning to the barrel. The stem 14, by its engagement with the head, provides a means whereby this head may be seated in the upper end of the barrel or removed therefrom so as to permit the traveling valve (not 60 shown) to be withdrawn from the well for repacking.

As a means for rotating this stem, it is provided with a head 15 formed with a ratchet shoulder 16. The stem 14 and its 70 head are provided with an axial bore 17 for the passage of a valve stem 18 and this valve stem, the upper end of which engages the sucker rod line 19, has at its lower end an enlargement 20 provided with a similar 75 ratchet shoulder 21 which may be engaged with the ratchet shoulder of the head 15 by lowering the valve stem to a predetermined degree. The structure just described is a structure of the head of the supplementary 80 working barrel known in the art as the McGregor barrel and forms no part of my invention except in combination with the modifications thereof, hereinafter to be referred to.

In the construction of the stem 14, this 85 stem is made of greater length and diameter than the stem ordinarily provided and the exterior of the head 15 thereof is provided with screw-threads 22 for coaction 90 with threads 23 of a socket 24 and is made removable. This socket is made of an external diameter equal to the external diameter of the barrel with which it is to be employed at its upper end and at its lower end 95 is made of an external diameter slightly less than the internal diameter of the cup washer 13 so that this lower end may project into the cup washer and force the washer into engagement with the head. The internal diameter of the socket, with the exception of the threaded upper end of the socket which engages with the head 15 of the stem, is made 100 slightly greater than the diameter of the head. The upper end of this socket is adapted for engagement with the usual sucker rod line 19, replacing the broken fragment of the valve stem which is withdrawn from the well. It will be obvious that by threading this socket upon the upper end of the 110 barrel, the entire barrel may be withdrawn.

It is pointed out that the frictional engage-

ment of the lower end of the socket with the cup washer and the frictional engagement of this cup washer with the upper end of the head will tend to prevent the stem 14 and head 11 from separating and thus to prevent accidental unscrewing of the barrel as the device is drawn from the well.

Since the construction hereinbefore employed is capable of a certain range of change and modification without materially departing from the spirit of the invention, I do not limit myself to such specific structure except as hereinafter claimed.

I claim:

15 A fishing tool for pulling a working barrel comprising a head having longitudinally extending ports, a cup valve for closing the

ports, and a guide member for the cup comprising a stem secured to the head and having an exteriorly threaded head at its upper end, said fishing tool comprising a socket having at its lower end an external diameter slightly less than the internal diameter of the cup valve and an internal diameter slightly greater than the head of the stem, the upper end of the socket being provided with an interiorly threaded portion for engagement with the threads of the head, the socket having means whereby it may be attached to a line.

In testimony whereof I hereunto affix my signature:

ERVIN L. BOETTLER.
